UNITED STATES PATENT OFFICE.

JAMES ROBERT CARDWELL, OF CHICAGO, ILLINOIS.

CAR-TRUCK.

No. 807,439.

Specification of Letters Patent.

Patented Dec. 19, 1905.

Application filed September 22, 1904. Serial No. 225,419.

To all whom it may concern:

Be it known that I, JAMES ROBERT CARDWELL, a citizen of the United States, residing at Chicago, in the State of Illinois, have invented certain new and useful Improvements in Car-Trucks, of which the following is a specification.

My invention relates to car trucks and particularly to the mounting of the truck bolster upon the frame which is supported upon the wheels. The principal objects of the invention are, to provide for the introduction of the springs between the bolster and its supports in such a manner as to economize space and allow of the use of longer springs than ordinary, to provide for placing the springs entirely within the bolster, to compact and simplify the bolster support and to generally improve the construction of car bolsters and trucks. These objects together with other advantages which will hereinafter appear I attain by means of the structure illustrated in preferred form in the accompanying drawings, wherein—

25 Figure 1 a partial side elevation of a common diamond frame wheel-truck and vertical section through the bolster and its supports, on line (1) in Figure 2, showing my improvements;

30 Figure 2 is a partial plan view and horizontal section taken along the line (2) in Figure 1;

Figures 3 and 4 are respectively a top plan view and a side elevation of the bolster in place in the truck frame.

35 For illustration of my invention I have shown a bolster made of I-beams and mounted in the common diamond frame. The bolster may be composed of the two side-beams 5, placed in the diamond frame as shown, and transmitting the weight of the car indirectly to the spring plank 6, which receives the weight at the two ends upon bearing blocks 7 which are provided with upright posts 8 working through openings in the bottom plate 9 of the bolster and directly engaging the floating spring plate 10, which works within the bolster and receives the pressure of coil springs 11 upon which rests the bearing block 12, preferably riveted directly to the flanges and web 40 of the I-beams 5 forming the bolster as shown in Fig. 1.

The outer flanges of the bolster 5 are notched to engage the column guides 13, so as to keep the bolster in place during the vertical vibration within the frame 14. The top spring plate 12 is fixed in place, but the lower one

10 is a floating plate and is preferably guided in vertical position by being provided with notches which engage guide lugs 15 fixed to the web of the I-beam 5.

60 It will be seen that by this construction I have placed the springs 11 entirely within the bolster and also within the diamond frame and that the pressure upon the springs being applied at the top of the bolster instead of at the bottom makes all the room within the diamond frame available for the springs except what is necessary to allow for the play between the bolster bottom plate 9 and the spring plank. The springs 11, the floating bearing plate 10, 70 and all movable parts inclosed entirely within the bolster itself, and of course the posts 8 need be only long enough to allow for the necessary play of the bolster upon its springs. The bolster is securely guided within the column guides 13, which also form the struts of the wheel truss or frame, and the floating plate is securely guided in its place within the bolster. There are no loose parts which may become disengaged from their places and the 75 whole truck is compact and is as rigid as is possible with the proper allowance of the vertical vibrations of the bolster with relation to the wheel frame.

Having thus described my invention and 80 illustrated its use, what I claim as new, and desire to secure by Letters Patent, is—

1. In a car truck a bolster composed of two I-beams and a set of springs confined between the said I-beams, and means for transmitting 90 the pressure upon the bolster through the springs to the wheel truss.

2. The combination with a bolster composed of two I-beams forming a box, springs within said box resting upon a floating plate, all confined in the box, and supporting posts extending within the bolster and engaging said floating plate, substantially as described.

3. The combination of a car bolster forming 100 a closed box at the ends, springs and a supporting plate therefor in the box, apertures in the base of the box, and a plate on the wheel truss having studs extending through said apertures and engaging the floating plate.

In testimony whereof I have hereunder 105 signed my name in the presence of the two subscribing witnesses.

JAMES ROBERT CARDWELL.
